UNITED STATES PATENT OFFICE.

STEPHEN KATKO, OF SOUTH BROWNSVILLE, PENNSYLVANIA.

LIFE-BOAT.

1,299,476.

Specification of Letters Patent.

Patented Apr. 8, 1919.

Application filed October 8, 1917. Serial No. 195,360.

To all whom it may concern:

Be it known that I, STEPHEN KATKO, a subject of the King of Hungary, residing at South Brownsville, in the county of Fayette and State of Pennsylvania, have invented 5 certain new and useful Improvements in Life-Boats, of which the following is a specification.

This invention relates to certain new and 10 useful improvements in life boats.

The primary object of the invention is the provision of a life boat adapted to be carried either upon the deck of a vessel or arranged adjacent thereto upon suitable davits 15 whereby persons may readily enter the life boat, which being arranged for floating upon the water, is easily steered and propelled by hand insuring the safety of the occupants thereof.

20 A further object of the device is the provision of a life boat of light weight and great strength arranged with a closed cabin and having an equilibrating attachment for preventing the life boat from capsizing.

25 With these general objects in view and others, that will appear as the nature of the invention is better understood, the same consists in the novel construction, combination and arrangement of parts hereinafter fully 30 described, illustrated in the accompanying drawings and pointed out in the appended claims.

In the drawing forming a part of this application and in which like numerals refer 35 to corresponding parts throughout the several views—

Figure 1 is a side elevation of the device with the outriggers and propellers detached.

Fig. 2 is a vertical central longitudinal sectional view thereof.

Fig. 3 is a longitudinal horizontal sectional view of the same provided with propellers.

Fig. 4 is a vertical transverse sectional view 45 of the device as shown in Fig. 3.

Fig. 5 is a top plan view of the device.

Fig. 6 is a vertical transverse sectional view thereof.

Fig. 7 is a detail side elevational view of a 50 portion of the boat showing one of the outriggers in position, and

Figs. 8 and 9 are enlarged detail views of the rudder controlling the members.

Referring more in detail to the drawings, 55 my invention provides a life boat 10 formed of any desirable material such as metal and

provided with a chamber 11 throughout substantially the entire interior thereof, serviceable as a cabin and having oppositely arranged sides or bunks 12 positioned therein. Suitable port windows 13 are arranged through the side of the hull 14 of the boat while a window 15 is arranged at the stern thereof. A ventilating outlet pipe 16 is positioned through the roof or deck 17 of the 60 boat while a hatchway or conning tower 18 is positioned adjacent the bow 19 thereof and windows 20 being provided upon all sides thereof for convenience in steering the boat.

Glass doors 21 are provided at the forward 70 end of the deck 17 for permitting access to the boat by way of the steps 22 within the cabin while a form of cleats or rounds 23 at the rear end of the cabin permit access to the window 15. A crescent shaped socket or oar 75 lock 24 is swiveled upon the bow 19 serviceable whenever desired while a ladder 25 is preferably dependably arranged at one side of the bow portion thereof. Short posts 26 are fixedly secured upright upon the deck 17 80 having rings 27 in the free ends whereby the boat may be readily suspended from the davits of a vessel, the boat also having wheels or rollers 28 upon the bottom thereof, which may be arranged in any direction desired, for 85 readily moving the boat upon the deck of a vessel such for instance upon a track adjacent the life boat lowering mechanism with which the vessel is provided.

A rudder 29 is swingingly carried by a 90 stern bracket 30 of the boat, being arranged with a rudder post 31 having cross arms 32 to each of which a steering cable 33 is connected for passing around the opposite sides of the boat and entering the same through 95 openings 34 adjacent the bow thereof, suitable pulley wheels 35 being carried by the hull 14 over which the cables 33 pass. Each of the cables 33 is provided with a separate winding drum 36 mounted within the cabin 100 11 upon posts 37 and mounted therein by means of a shaft 38 having an end wheel 39 adapted for turning the drum and winding the cable thereon. A toothed wheel 40 is provided upon each of the shafts 38 and is arranged with a retaining dog 41. It will be understood that by means of this arrangement, a person within the cabin 11 may readily ascertain the position of the boat for purposes of steering through the hatchway 110 windows 20 and in which position the said person may readily turn the wheels 39 for

adjusting the rudder 29 and steering the life boat in a suitable course, the dogs 41 being preferably inoperative during the steering operations.

5 An equilibrating device is provided for the boat in the nature of an outrigger construction. The device has two main floats 43 hinged at opposite points 42 upon the hull 14 of the ship. An arch-shaped connector 44 10 is pivoted centrally to a post 45 upon the deck 17 with its opposite ends connected by hinges to the main floats 43 on their upper concave sides 46.

Auxiliary floats 47 are connected by hinges 15 to the hull 14 at points 48 and beneath the point of connection with the floats 43.

Links 49 connect the main and auxiliary floats together to form a rigid construction, it being evident however, that the position of 20 the floats are such that the main floats 43 rest upon the surface of the water while the auxiliary floats are submerged, this construction serving to stabilize the boat, preventing it from capsizing when in rough 25 water. As the distance between any two of the float's connections with the hull cannot be changed, movement of the floats relative to one another will be impossible; thus the floats on one side will serve to prevent a complete tilting of the boat should it rock in that direction, the floats on the opposite side having the same action when the boat tilts in that direction.

If found advisable, a hook 50 or stay member 30 may be hinged to the yoke 44 and removably engaged with the deck 17 by means of a connecting ring 51 carried thereby, this hook or stay member serving to hold the outrigger against displacement.

40 Crank shafts 52 are journaled through the opposite sides of the hull 14 and bearings 53 arranged externally thereof, paddle wheels 54 being secured to the outer free ends of the said shafts while turn wheels 55 are secured 45 to the inner ends thereof. Journaling posts

56 are provided within the cabin for the shafts 52 while end-engaging sleeves 57 are mounted upon the cranks for use in operating the shafts, the seats 12 being employed if desired by the operator of the paddles. A 50 figure-head 58 preferably in the form of an eagle is arranged on the conning tower 18.

It will be seen that a serviceable life boat is arranged which may be of great service in time of ship wreck as the boat can be filled 55 with passengers and allowed to float when the vessel carrying the same sinks, the windows of the life boat being air and water tight while the pipe 16 provides for suitable 60 ventilation. The boat being readily propelled by the passengers by means of the propellers 54 steered by means of the rudder 29 the occupants of the device will be saved from drowning.

What I claim as new is:

1. A life boat comprising a hull having a cabin, main arcuate floats arranged at opposite sides of the hull, auxiliary floats connected to the hull beneath said main floats, a link connection between the respective main 70 floats and auxiliary floats, and a yoke centrally secured to the boat, with its opposite ends secured to the upper sides of the main floats.

2. A life boat comprising an inclosed hull 75 having a deck, a post arranged upright on the said deck, main floats connected to the opposite sides of the boat and arranged at an angle thereto and being of arcuate formation in cross section, a yoke centrally connected 80 to the said post with its free ends having connections to the upper sides of said main floats, auxiliary floats connected to the boat beneath the main floats, link connections between the main and auxiliary floats, and a 85 removable stay connection between the yoke and the deck of the boat, whereby the floats and yoke are further held against movement.

In testimony whereof I affix my signature.

STEPHEN KATKO.
